UNITED STATES PATENT OFFICE

CHARLES ANDREW VOLZ, OF BIRMINGHAM, MICHIGAN

LEVEL DEVICE

Application filed May 1, 1929. Serial No. 359,660.

The device forming the subject matter of this application is a level, and one object of the invention is to provide a novel means whereby the level vial may be illuminated at 5 the will of an operator. Another object of the invention is to provide novel means for mounting the level vial for adjustment.

It is within the province of the disclosure to improve generally and to enhance the utility of devices of the sort to which the present 10 invention appertains.

With the above and other objects in view, which will appear as the description proceeds, the invention resides in the combination and arrangement of parts and in the details of construction hereinafter described and claimed, it being understood that changes in the precise embodiment of the invention herein described, may be made within the 20 scope of what is claimed, without departing from the spirit of the invention.

In the accompanying drawings:

Figure 1 shows in side elevation, a device constructed in accordance with the invention;

Figure 2 is a top plan;

Figure 3 is a longitudinal section on an enlarged scale, on the line 3—3 of Figure 4;

Figure 4 is a top plan on an enlarged scale, 30 the cover plate having been removed, and parts being broken away;

Figure 5 is a transverse section on the line 5—5 of Figure 3;

Figure 6 is a section on the line 6—6 of 35 Figure 5; and

Figure 7 is a perspective view showing the vial.

The level forming the subject matter of this application comprises a stock 1 having 40 a longitudinal compartment 2. The compartment 2 has transverse enlargements 30, which are shown in Figure 4. The compartment 2 extends but part way through the stock 1, from edge to edge, as Figures 5 and 45 3 will show. In one edge of the stock 1 there is a recess 3, and in the opposite edge of the stock there is a hole 4 which communicates with the recess 2. There is an opening 5 that extends entirely through the stock 1 50 from side to side, the opening 5 communica-

cating with the compartment 2. The opening 5 is flared at its ends, as shown at 6. In one edge of the stock 1 there is a notch 7 which, as disclosed in Figure 6, is approximately semi-circular in shape. The notch 7 is flared at its ends, as shown at 8. The notch 7 communicates with the compartment 2.

A vial holder is provided, and is shown in Figure 7 of the drawings. The vial holder includes a plate-like body 9 which is cut transversely, as indicated at 10, to form spaced arms 11, and a support 15 between the arms. The arms project in one direction, and the support 15 projects in an opposite direction. The ends of the arms 11 are turned on themselves to form tubular sockets 12 in which the vial 14 is held. The support 15 is curved so as to conform to the curvature of the notch 7, the body 9 of the vial holder extending downwardly into the compartment 2, along one wall of the compartment, as shown clearly in Figure 5 of the drawings. The support 15 has openings 16 through which extend headed securing elements 17, such as screws (Figure 6), the securing elements 17 entering the stock 1, the openings 16 in the support 15 being slightly larger in diameter than the screws 17, so that, when the screws are loosened, the support 15 may be shifted circumferentially of the notch 7, thereby to adjust the vial 14.

The numeral 18 marks, generally, a leveling device like the one hereinbefore described, the leveling device 18 cooperating with the opening 5, whereas the leveling device 9—14 85 cooperates with the notch 7.

A plate 19 is held in the recess 3 by securing members 20 and constitutes a closure for the compartment 2. The plate 19 has an opening 21 through which the level vial 14 90 can be seen. The vial 14 is used for leveling, whereas the device shown at 18 is used for plumbing, according to a custom well understood by mechanics. The numeral 22 marks a switch tongue which extends along the under side of the plate 19, one side of the tongue 22 being secured at 23 to the plate. The tongue 22 has an arm 24 arranged at right angles to the tongue, the arm 24 terminating in a finger which outstands from the arm 24 95 100

in parallel relation to the tongue 22. The finger 25 carries a socket 26 in which may be mounted an electric lamp 27, the butt contact of the lamp being shown at 28. The switch tongue 22 is made of metal as is the switch member 29, in the form of a strip, extended under the base of the compartment 2 in contact with the socket 1. The switch member 29 has U-shaped button 31 which projects into the opening 4. The switch member 29 has some resiliency. The button 31 is prolonged to form an arm 32 at right angles to the switch member 29 and parallel to the arm 24, the arm 32 terminating in a finger 33 adapted to cooperate with the butt contact of the lamp 27. Cells of battery are interposed between the switch tongue 22 and the switch member 29.

It will be obvious that an operator may apply pressure by the thumb or finger to the button 31, pushing the button 31 inwardly, the switch member 29 springing until the finger 33 comes into contact with the part 28, the lamp 27 being lighted so as to illuminate either the vial 14 or the device 18, when the instrument is used in a dark place.

The general construction is such that either the plumbing vial or the level vial may be illuminated, and the structure shown in Figure 7 affords a convenient means whereby the vials may be adjusted.

Having thus described the invention, what is claimed is:—

1. In a device of the class described, a stock having a compartment, the stock being provided in one edge with a hole communicating with the compartment, switch members in the form of strips disposed in approximately parallel relation in the compartment, the strips having arms that extend inwardly toward each other, an electric lamp carried by the arm of one strip, the other strip being resilient and having a button to which the hole gives access, whereby said other strip may be flexed inwardly to bring the arm thereof into circuit-closing relation to the lamp, and to light the lamp, a battery electrically engaged between the strips, and a leveling device carried by the stock and located close enough to the lamp to be lighted thereby.

2. A device of the class described, constructed as set forth in claim 1, and further characterized by the fact that the said other strip is detachably and removably mounted in the compartment, being held therein by the pressure of the battery and by the engagement of the button in the hole, and means for holding the battery against movement with respect to said other strip.

In testimony that I claim the foregoing as my own, I have hereto affixed my signature.

CHARLES ANDREW VOLZ.
